ELECTRON DIFFRACTION DETECTOR
SYSTEMRichard L. Longini, Pittsburgh, Pa., assignor to
Westinghouse Electric Corporation, East Pitts-
burgh, Pa., a corporation of Pennsylvania

Application June 30, 1949, Serial No. 102,292

8 Claims. (Cl. 250—49.5)

1

My invention relates to electron diffraction cameras, and in particular relates to arrangements by which the variation of intensity of the diffraction pattern with angular divergence may be registered graphically and measured.

In electron diffraction cameras a fine beam of constant voltage electrons is projected against a specimen of a substance making a small angle with the surface of which it is desired to obtain a pattern. It is found that electrons are diffracted in such an arrangement at various angles from the axis of the impinging beam in such a way as to produce conical streams of electrons diverging at various angles to the axis of the impinging stream. The intensity distribution of the diffracted electrons at various angles relative to the axis of the cones is found to be a characteristic of the material undergoing study and may be referred to as the electron diffraction pattern of the surface of that material.

In accordance with the prior art, such diffraction patterns have been recorded by positioning photographic films or plates to intersect the electron cones. However, this procedure is unsatisfactory in that it gives only rough measurements of intensity variation, and is somewhat time consuming because it is necessary to develop the photographs before the desired information as to the diffraction pattern is obtained. The procedure becomes especially unsatisfactory if, as is sometimes the case, the physical characteristics of the sample being studied are changing with time. It is obvious that in any case where the changes are rapid it becomes practically impossible to record the diffraction patterns accurately.

In application Ser. No. 120,123, filed June 29, 1949, assigned to the same assignee as the present application and entitled "Electron Diffraction Camera," John W. Coltman discloses an arrangement in which the system of conical electron beams forming such a diffraction pattern impinges upon a plate electrode having a small aperture through which a small section of the beam is allowed to pass to impinge upon a collector electrode connected to a measuring oscilloscope. By causing the electron beam system to be magnetically deflected so that this plate aperture is in effect displaced along a radius of the electron beam system, the variations in the intensity of the latter are recorded on the oscilloscope.

While this arrangement possesses great utility, it is usually desired to plot the number of electrons deflected at any given angle against

2

such angular deflection. In such case the arrangement has the undesirable feature that, as the aperture of fixed size is displaced radially outward from the center of the beam system, it subtends a constantly decreasing angle about the central axis of the electron beam and, accordingly, the response of the oscilloscope represents a continually decreasing fraction of the current flowing in the various electron cones as the aperture moves from the center to the peripheral portions of the beam. To put the matter another way, it is necessary to multiply the current reading, which the oscilloscope registers for any angular deflection, by the value of the angle itself, in order to obtain a graph in which the number of electrons diffracted through any angle are plotted against the angular measurement. One principal feature of my invention is the provision of an arrangement whereby an oscilloscope records a graph relating the diffraction angle with the total number of electrons diffracted through the angle.

One object of my invention is, accordingly, to provide a novel apparatus for recording, in an electron diffraction apparatus, the relation between diffraction angle and total number of electrons diffracted through that angle.

Another object of my invention is to provide a novel form of electron diffraction camera which directly registers the relationship between diffraction angle and the fraction of electrons deflected through such an angle.

Still another object of my invention is to provide a novel electron diffraction camera which records on the screen of an oscilloscope a curve truly representing, as abscissa, the diffraction angle, and as ordinate the fraction of electrons diffracted through that angle.

Still another object of my invention is to provide a graphical electron diffraction pattern registering device which records diffraction angle as abscissa against electron current as ordinate, and in which the sensitivity for the ordinate scale remains the same throughout the abscissa range.

Other objects of my invention will become apparent upon reading the following description taken in connection with the drawings, in which:

Fig. 1 is a diagram useful in explaining the principles of my invention;

Fig. 2 is an illustration of a typical graphical curve appearing on an oscilloscope screen in the apparatus embodying my invention;

Fig. 3 is a schematic representation of one form of apparatus embodying the principles of my invention;

Fig. 4 is a detailed illustration of one form of

3

aperture plate forming a part of the embodiment shown in Fig. 3; and

Fig. 5 is a schematic illustration of a modified form of the embodiment shown in Fig. 3.

Referring in detail to Fig. 1, a sample 1 of material which it is desired to obtain an electron diffraction pattern is supported by any suitable means (not shown) in the path of an extremely fine electron beam 2. So-called electron guns and other arrangements for producing such fine streams of electrons are well-known in the electronics art today and are believed to require no separate description.

The above-mentioned sample and electron beam may be enclosed within a suitable container 3 which may be vacuum tight if desired and which is believed to require no detailed description since such arrangements are well-known in the electronics art today. A publication entitled "RCA Electron Diffraction Unit" published by Radio Corporation of America, Rockefeller Center, New York city, describes an apparatus employing such an electron beam.

After being diffracted by the surface of the sample 1, it will be found that the electrons are diffracted in such a way as to produce, in effect, a number of half cones having various apex angles, coaxial to the axis of the original electron beam 2. A metallic plate 4 may be supported at a suitable distance from the sample 1 in a position normal to the axis of the above-mentioned cones. If a fluorescent plate were supported on the plate 4, it would be intersected by the conical beams of electrons above-mentioned and would be found to show successive rings representing the traces of these cones at the plate 4. Such arrangements as I have so far described are found in some diffraction cameras of the prior art on which my arrangement is an improvement.

In accordance with the principles of my invention I provide the plate 4 with a V-shaped slot of angle θ , the apex of the V being positioned on the axis of the conical electron beam system. It will readily be seen that the portions of the electron beam system at any radial distances of different apex angles which pass through the V-shaped slot are the same fraction

$$\frac{\theta}{\pi}$$

of the total number of electrons composing the half cone.

In order to obtain a record of the variations of the electron current with radial distance from the axis of the cone, I provide an aperture plate 5 which is arranged to move from the apex of the V-shaped slot to its periphery. As just remarked the electron current passing through such an aperture will be, at any radial distance, a definite fraction

$$\frac{\theta}{\pi}$$

of the total electron current in the cone striking plate 4 at that radius. By collecting the electron current passing through this aperture, I can, accordingly, obtain a curve in which the diffraction angle is recorded as abscissa, and the total number of electrons diffracted at that angle is recorded as ordinate. Fig. 2 illustrates such a graph on the screen of an oscilloscope.

To obtain the best record of the electron current at any radial distance r from the axis of

4

the cone, the aperture in the plate 5 should be curved to correspond with the radial distance that it occupies at any particular instant in its scanning movement. With a simple aperture of unchanging size and shape in the plate 5, this ideal condition is not obtained; but it can be very closely approximated by making the aperture in the plate 5 of curved form. It is possible to show that the minimum deviation of the aperture from its ideal value as it moves radially outward from the apex of the V is attained if the slot in the plate 5 has a radius equal to approximately $0.83R$ where R is the radius of the outermost electron cone which it is desired to record. The angle between the sides of the V-shaped notch in the plate 4 should, of course, be made as small as is consistent with obtaining the desired sensitivity in the instrument which records the electron current flowing through the aperture in plate 5.

Fig. 3 shows diagrammatically an apparatus embodying the ideas schematically described in connection with Fig. 1. The sample of material 1 is held by supports (not shown) in the path of an electron beam by an electron gun system 2a of a type too well-known in the art to require detailed description. This arrangement is enclosed within a container 3 which may, if desired, be made vacuum tight and which supports the plate 4. The V-shaped aperture is shown in Fig. 3 at a position displaced 90° from that which is illustrated in Fig. 1. The plate 5 is supported for sliding movement along the lower face of the plate 4 and both plates 4 and 5 are connected through a suitable voltage source (not shown) to the source of electron stream 2. The plate 5 is insulatingly supported on a collector electrode 6 sliding on insulated supporting rods 7 held by a suitable framework 8 based on the floor of the container 3. The container 3 may be at ground and the rest of the system at a high negative voltage. A rod 9 of insulating material passes through a suitable bushing 11 in the wall of the container 3 and is arranged to slide the plate 5 and collector electrode 6 radially along the bisector of the V-shaped opening so that the aperture in the plate 5 traverses the entire distance from the axis 12 of the conical electrode beam system to the point of incidence of the most widely diffracted electron which it is desired to record. The rod 9 may be arranged to be moved thus by attachment to the core 13 of a reciprocating motor having winding 14. Beyond the core 13, the rod 9 may extend through a suitable bearing 15 and be arranged to move a contact 16 along a potential divider 17 fed with direct current from a suitable voltage source 18. One end of the voltage divider 17 is grounded. The horizontal deflection plates of an oscilloscope 19 are connected between the movable contact 16 and the grounded end of the potential divider 17. The winding 14 of the reciprocating motor is supplied with current through a suitable circuit interrupter 21 which is arranged in a manner well known in the art to repeatedly energize and de-energize the winding 14 to thereby reciprocate the collector electrode 6 and plate 5 along the radius of the conical electron beam system above mentioned.

The vertical plates of oscilloscope 19 are respectively connected to ground and to the collector electrode 6 through a suitable amplifier 20. A suitable bias spring 22 forming a part of the reciprocating motors is arranged to return the core 13 to its initial position after each energiza-

tion of the winding 14 by the circuit interrupter 21.

While I have described a reciprocating motor as employed to cause the radial movement of the rod of the collector electrode 6, it will be obvious to those skilled in the art that any other suitable arrangement for causing such motion may be employed.

A moment's consideration will show that as the reciprocating motor moves the collector electrode 6 radially outward along the radius of circles of intersection of the conical electron beam in the container 3, the deflecting voltage impressed on the horizontal plates of oscilloscope 19 will deflect the electron beam thereof horizontally to produce abscissas corresponding to radial distances r along the plate 4 and, to a high degree of approximation, corresponding to the apex angles of the various conical electron beams. Simultaneously, the collector electrode 6 will receive through the aperture plate 5 an electron current proportional to the total electron flow incident upon plate 4 at the radial distance r ; and this current will produce vertical deflections of corresponding magnitude on the screen of the oscilloscope 19. In order to give a vertical deflection proportional to the fraction of current in a given ring the detector aperture must move with uniform radial velocity.

There will, accordingly, be registered on the screen of the oscilloscope a graph correctly representing the variation with diffraction angle of the electron current in the conical electron beams.

While a single circular aperture in the plate 5 having a radius of 0.83 times that corresponding to the maximum electron cone which it is desired to record will be found satisfactory for most purposes, it is possible to provide an aperture in plate 5 which will even more closely approximate the ideal condition by employment of the configuration shown in Fig. 4. The aperture is split up into three different portions. The inner portion 25 of the aperture in plate 5 will alone be exposed during the first one-third of the travel of the collector electrode 6, while the collector electrode 6 is moved from the apex of the V for about one-third of its total length radially outward from the apex of the V-shaped notch in plate 4; then, during the next one-third of said movement, the intermediate portion 26 of the said aperture likewise collects electrons; and finally, during the last one-third of the radial movement of the collector electrode 6, all three portions 25, 26 and 27 of the aperture in plate 5 will pass electrons.

The inner portion 25 of this aperture should preferably have a radius $R1$ which is 0.83 times one-third of the maximum radial movement of the collector electrode 6 from the axis to the outermost cone, and its length should correspond to the width of the V-shaped aperture in plate 4 corresponding to that one-third. The radius $R2$ of the portion 26 should be 0.83 times two-thirds of the total radial travel of the collector electrode 6 and the slots 25 and 26 should together span the width of the V-shaped aperture in plate 4 at the said two-thirds of the total travel. The radius $R3$ of the portions 27 of the aperture in plate 5 should be 0.83 times the total radial travel of the collector electrode 6, and their length should be such as to span the distance between the sides of the V-shaped aperture in plate 4 at said maximum radial travel. The curves of the portions 25, 26 and 27 should be tangent to each

other at their midpoints and the width of the aperture slots should be the same. It will be clear that, while I thus describe the aperture as subdivided into three sections 25, 26, 27, the subdivision may be carried to any number, and that at the limit of subdivision an aperture having continuously curved sides will result.

In Fig. 5 I show a modification of my invention which avoids the necessity for providing for mechanical movement of the collector electrode 6 and also shows an arrangement for deriving an amplified control current for the oscilloscope. In this arrangement, the elements 1, 2, 2a and 4 are the same as the corresponding elements in Fig. 3 already described. However, instead of using a moving collector electrode 6, I provide a stationary collector electrode comprising a fluorescent screen 31 positioned at a substantial distance below the plate 4 and preferably on the extension of the axis of the diffraction electron cones. Between the screen 31 and the plate 4 I provide a magnetic field which is perpendicular to the plane bisecting the angle between the sides of the V-shaped aperture in the plate 4. This magnetic field may be conveniently set up by a pair of windings 32 (only one of which is shown) which are supplied with current of saw-tooth waveform from a saw-tooth generator 33 of a type well-known in the electronics art. The same saw-tooth generator supplies voltage to the horizontal deflection plates of the oscilloscope 19. The vertical deflection plates of the oscilloscope 19 are connected to be energized by current proportional to but many times larger than that incident on screen 31. The amplifying means comprises a photomultiplier 35 exposed to radiation from the fluorescent screen 31 and having its anode connected to one of the vertical plates of the oscilloscope 19 and through a resistor 36 to the positive terminal of a voltage source (not shown). The negative terminal of this voltage source is connected through ground to the cathode of the tube 35 and to the other vertical plate of the oscilloscope 19. Such a photomultiplier is believed to be too well-known to require detailed description, but examples are described in the above-entitled application of John W. Coltman entitled "Electron Diffraction Camera," filed June 29, 1949, and in an application Serial No. 758,014 by Marshall and Coltman, filed June 30, 1947, for an X-Ray Thickness Gage and which is now U. S. Patent 2,512,355, granted June 20, 1950.

The screen 31 is supported by the electrode plate 34 which is grounded and is provided with an aperture exactly like those already described as present in the plate 5 in Fig. 1.

The magnetic field from the winding 32 will periodically change from a value of zero to one sufficient to deflect through the aperture in plate 34 the electrons which pass through the V-shaped aperture in plate 4 from the electron cone of widest aperture. When the current in winding 32 has its zero value, the electrons at the central axis of the conical diffraction electron beam system will pass through the narrow aperture in plate 4 corresponding to the tip of the V-shaped slot therein and will then pass through the aperture in plate 34 to collector electrode 31 and cause a vertical deflection from the electron beam from the screen of oscilloscope 19. Correspondingly, the deflection voltage applied to the horizontal deflecting plates in oscilloscope 19 will be zero and the electron beam will be at one extreme of its horizontal movement.

As the magnetic field due to windings 32 increases in value, the electrons passing through the aperture in plate 4 at great radial distances from its apex will be deflected through the aperture in plate 24 to collector electrode 31. At the same time, the luminous spot on the screen of oscilloscope 19 will move to greater and greater distances along its horizontal path. There will, accordingly, be recorded on the screen of oscilloscope 19 a curve corresponding to the electron current passing through the V-shaped aperture in plate 4 at greater and greater radial distances from the apex thereof.

The V-shaped notch in plate 4 insures that the current reaching collector electrode 31 is a constant fraction of the total electron flow in the conical beam system at the radial distance corresponding to horizontal deflections of the spot on the screen of the oscilloscope 19.

Since numerous changes may be made in the above-described construction, and different embodiments of the invention may be made without departing from the spirit and scope thereof, it is intended that all matter contained in the foregoing description or shown in the accompanying drawings shall be interpreted as illustrative and not in a limiting sense.

I claim as my invention:

1. In an electron diffraction measuring device, means for producing a conical electron beam system corresponding to the diffraction pattern of a specimen under test, means for intersecting said electron beam system with a conducting plate having a V-shaped slot with its apex on the axis of said conical beam system, means for scanning said slot lengthwise thereof by an aperture restricted in its dimension which is parallel to the bisector of said slot, and means for measuring current flow through said aperture.

2. In an electron diffraction measuring device, means for producing a conical electron beam system corresponding to the diffraction pattern of a specimen under test, means for intersecting said electron beam system with a conducting plate having a V-shaped slot with its apex on the axis of said conical beam system, means for scanning said slot lengthwise thereof by an aperture restricted in its dimension which is parallel to the bisector of said slot, and means for plotting current flow through said aperture against movement of said scanning means.

3. In an electron diffraction measuring device, means for producing a conical electron beam system corresponding to the diffraction pattern of a specimen under test, means for intersecting said electron beam system with a conducting plate having a V-shaped slot with its apex on the axis of said conical beam system, means for scanning said slot lengthwise thereof by an aperture restricted in its dimension which is parallel to the bisector of said slot, and means for plotting current flow through said aperture against movement of said scanning means, said aperture having a radius which is 0.83 times the radius of the trace on said plate of the widest angled cone of interest in said conical beam system.

4. In an electron diffraction measuring device, means for producing a conical electron beam system corresponding to the diffraction pattern of a specimen under test, means for intersecting said electron beam system with a conducting plate having a V-shaped slot with its apex on the axis of said conical beam system, means for scanning said slot lengthwise thereof by an aperture restricted in its dimension which is parallel to the

bisector of said slot, and means for plotting current flow through said aperture against movement of said scanning means, said aperture comprising a compound curve composed of a plurality of arcs which are tangent to each other at their midpoints.

5. In combination with means for producing an electron diffraction pattern having the form of a conical electron beam system, an electrode having a V-shaped aperture with the apex of the V positioned in the axis of said conical beam system, means for producing a magnetic field perpendicular to the plane which bisects said V-shaped slot, said magnetic field being located on the side of said electrode remote from the apex of said conical beam system, a plate electrode having an aperture therein which is narrow in the direction of the bisector of said V-shaped slot and which is located in the region of the central axis of said conical beam system, a collector electrode upon which electrons passing through said aperture are incident after passing through said aperture and current measuring means connected to said collector electrode.

6. In combination with means for producing an electron diffraction pattern having the form of a conical electron beam system, an electrode having a V-shaped aperture with the apex of the V positioned in the axis of said conical beam system, means for producing a magnetic field perpendicular to the plane which bisects said V-shaped slot, said magnetic field being located on the side of said electrode remote from the apex of said conical beam system, a plate electrode having an aperture therein which is narrow in the direction of the bisector of said V-shaped slot and which is located in the region of the central axis of said conical beam system, a collector electrode upon which electrons passing through said aperture are incident after passing through said aperture, a source of saw-tooth voltage connected to induce said magnetic field, and means for graphically plotting the current from said collector electrode against the strength of said magnetic field.

7. In combination with means for producing an electron diffraction pattern having the form of a conical electron beam system, an electrode having a V-shaped aperture with the apex of the V positioned in the axis of said conical beam system, means for producing a magnetic field perpendicular to the plane which bisects said V-shaped slot, said magnetic field being located on the side of said electrodes remote from the apex of said conical beam system, a plate electrode having an aperture therein which is narrow in the direction of the bisector of said V-shaped slot and which is located in the region of the central axis of said conical beam system, a collector electrode upon which electrons passing through said aperture are incident after passing through said aperture, a source of saw-tooth voltage connected to induce said magnetic field and an oscilloscope having one pair of deflecting plates energized from a source of saw-tooth voltage and another pair of plates energized proportionately to the output current through said collector electrode.

8. In combination with means for producing an electron diffraction pattern having the form of a conical electron beam system, an electrode having a V-shaped aperture with the apex of the V positioned in the axis of said conical beam system, means for producing a magnetic field perpendicular to the plane which bisects said V-

shaped slot, said magnetic field being located on the side of said electrode remote from the apex of said conical beam system, a plate electrode having an aperture therein which is narrow in the direction of the bisector of said V-shaped slot and which is located in the region of the central axis of said conical beam system, said aperture extending in a direction normal to the plane bisecting said V-shaped notch for a distance equal to the width of said notch where it is intersected by the cone of widest aperture in said conical electron beam.
